DESIGN FOR A BICYCLE HANDLE BAR BRACE

Donald L. Miller, Des Moines, Iowa

Application October 3, 1938, Serial No. 80,216

Term of patent 14 years

To all whom it may concern:

Be it known that I, Donald L. Miller, a citizen of the United States and resident of Des Moines, Polk County, Iowa, have invented a new, original, and ornamental Design for a Bicycle Handle Bar Brace, of which the following is a specification, reference being had to the accompanying drawing, forming a part thereof.

Fig. 1 is a front view of the bicycle handle bar brace showing my new design.

Fig. 2 is a side view of the bicycle handle bar brace.

Fig. 3 is a rear view of Fig. 2, a portion being broken away for convenience in illustrating.

I claim:

The ornamental design for a bicycle handle bar brace, substantially as shown.

DONALD L. MILLER.
